UNITED STATES PATENT OFFICE.

WERNER H. BALZER, OF NEW YORK, N. Y., ASSIGNOR TO THE ANSONIA CLOCK COMPANY, OF NEW YORK, N. Y., A CORPORATION OF CONNECTICUT.

DESIGN FOR A CLOCK CASE.

Application filed December 17, 1927. Serial No. 24,515. Term of patent 14 years.

To all whom it may concern:

Be it known that I, WERNER H. BALZER, a citizen of the German Republic, residing in the city of New York, county and State of New York, have invented a new, original, and ornamental Design for Clock Cases, of which the following is a specification, reference being had to the accompanying draw-

ing, forming part thereof.

The figure is a perspective view of a clock case, showing my new design.

I claim:

The ornamental design for a clock case, as shown.

WERNER H. BALZER.
